US00D625251S

(12) **United States Design Patent**
Workman et al.

(10) **Patent No.:** **US D625,251 S**
(45) **Date of Patent:** **** Oct. 12, 2010**

(54) **HINGED PHOTOVOLTAIC ARRAYS**

(75) Inventors: **Robert Emmett Workman**, Morgan, UT (US); **Norm Krantz**, Logan, UT (US); **Arthur Lee Dietrich-Croy**, Salt Lake City, UT (US); **John R. Omdahl, II**, Lindon, UT (US); **Michael S. Horito**, Provo, UT (US)

(73) Assignee: **Goal Zero LLC**, Bluffdale, UT (US)

(**) Term: **14 Years**

(21) Appl. No.: **29/350,407**

(22) Filed: **Nov. 16, 2009**

(51) **LOC (9) Cl.** **13-02**

(52) **U.S. Cl.** **D13/102**

(58) **Field of Classification Search** **D13/102, D13/101, 103, 107, 108, 199; 136/206, 243, 136/244, 245, 252; 320/101, 102, 114, 115, 320/120**

See application file for complete search history.

(57) **CLAIM**

The ornamental design for hinged photovoltaic arrays, as shown and described.

DESCRIPTION

FIG. 1 is a perspective view of a hinged photovoltaic arrays showing our new design;

FIG. 2 is a front elevational view of the hinged photovoltaic arrays of FIG. 1;

FIG. 3 is a back elevational view of the hinged photovoltaic arrays of FIG. 1;

FIG. 4 is a right side elevational view of the hinged photovoltaic arrays of FIG. 1;

FIG. 5 is a left side elevational view of the hinged photovoltaic arrays of FIG. 1;

FIG. 6 is a top view of the hinged photovoltaic arrays of FIG. 1; and,

FIG. 7 is a bottom view of the hinged photovoltaic arrays of FIG. 1.

1 Claim, 5 Drawing Sheets
